(57) **CLAIM**

The ornamental design for a tubular bag with pleated panel, as shown and described.

DESCRIPTION

FIG. 1 is a right perspective view of the tubular bag with pleated panel, shown in an uncinched state;

FIG. 2 is a right side perspective view of the tubular bag with pleated panel, shown in a cinched state.

FIG. 3 is a left side perspective view of FIG. 1;

FIG. 4 is a left side perspective view of FIG. 2;

FIG. 5 is a front elevational view of the tubular bag with pleated panel, shown in an uncinched state;

FIG. 6 is a front elevational view of the tubular bag with pleated panel, shown in a cinched state;

FIG. 7 is a rear elevational view of the tubular bag with pleated panel, shown in an uncinched state;

FIG. 8 is a rear elevational view of the tubular bag with pleated panel, shown in a cinched state;

FIG. 9 is a top perspective view of FIG. 5;

FIG. 10 is a bottom perspective view of FIG. 6;

FIG. 11 is a top perspective view of FIG. 7;

FIG. 12 is a bottom perspective view of FIG. 8;

FIG. 13 is a front elevational view of the tubular bag with pleated panel as in FIG. 5, now showing an alternative arrangement in which the front panel has shading indicating a first preselected fabric, the bag has shading indicating a second preselected fabric, and the bottom of the bag has shading indicating a third preselected fabric;

FIG. 14 is a bottom perspective view of FIG. 13;

FIG. 15 is a front elevational view of the tubular bag with pleated panel as in FIG. 5, now showing an alternative arrangement wherein the bag is fuller; and,

FIG. 16 is a bottom perspective view of FIG. 15.

The broken line showing of hardware (e.g. zipper) including the carry strap extensions and stitching and the position of the hardware relative to the claimed design and any other broken lines are to show environment only and are not part of the claimed design.
